His Attorney.

UNITED STATES PATENT OFFICE

JAMES T. SERDUKE, OF SCHENECTADY, NEW YORK, ASSIGNOR TO GENERAL ELECTRIC COMPANY, A CORPORATION OF NEW YORK

SOUND REPRODUCING AND RECORDING DEVICE

Application filed January 22, 1929. Serial No. 334,250.

My invention relates to apparatus for reproducing or recording sound, and has for its principal object the provision of an improved apparatus capable of faithfully responding to electric impulses dependent on sound.

Various devices for the reproduction or recording of sound, operated by electric impulses, have been provided in the past. 10 Many of these devices include an armature or coil mounted to move in a magnetic field and connected to a diaphragm or recording stylus. Such devices have the disadvantage that they are complicated, require accurate 15 workmanship, and are expensive.

In accordance with my invention these difficulties are minimized by providing, for such devices, a movable member or members composed of a material whose physical 20 dimensions vary in response to variations in a magnetic field acting thereon, and arranging such member or members to operate a sounding diaphragm or a recording stylus.

My invention will be better understood 25 from the following description when considered in connection with the accompanying drawing and its scope will be pointed out in the appended claims.

Referring to the drawings, Fig. 1 illustrates a loud speaker embodying my invention in its simplest form; Fig. 2 is a modification thereof; and Fig. 3 illustrates a phonograph record cutter embodying my invention.

35 Fig. 1 illustrates a loud speaker including a rigid conical diaphragm 10 which may be supported by a flexible annulus surrounding its base and a coil 11 adapted to receive the electric impulses which are to be converted 40 into sound. The coil 11 is arranged to create a magnetic field which acts upon a driving member 12. Member 12 is placed through the center of the coil 11, is rigidly mounted at one end to a base 13 and at the 45 other end is attached to the cone 10.

The member 12 may be either a rod or tube which is capable of varying its length in response to variations in the magnetic field created by currents in the coil 11. In the 50 investigations of the magneto-striction char-

acteristics of metals, it has been found that some metals elongate with an increase of intensity of a magnetic field acting thereon and others decrease in length with the same increase in intensity. The theory of such 55 expansion or contraction is not clearly understood but has been proven to exist. In my investigations I have found for instance, that alloys comprising between 40% and 70% cobalt alloyed with either iron or nickel, 60 expand as much as .00084 millimeter per centimeter of length for an increase of 100 to 200 gauss in intensity of the magnetic field. Nickel on the other hand contracts approximately the same amount for the same 65 increase in magnetic intensity. This contraction and expansion varies with different alloys and varies even with different treatments of the same alloy.

Fig. 2 illustrates a modification of the invention in which member 12 is replaced by a driving mechanism including tubes or rods 14 and 15 of which 14 elongates and 15 contracts with the same variation in the field 70 intensity.

Caps 16 and 17 are mounted upon the upper ends of the magneto-strictive members 14 and 15 respectively, and support a member 18 by means of spring members 19 and 20. The latter are spaced apart, and are 80 rigid in a vertical plane but resilient horizontally. The opposite ends of the members 14 and 15 are imbedded in a member 25 which in turn is supported by base 13. In operation therefore, the caps 16 and 17 and 85 therefore springs 19 and 20 move in opposite directions under the influence of the magnetic field variations and thereby move the member 18, the free end of which is caused to swing or vibrate and may be caused to 90 drive the cone 10 by means of a driving rod 21.

Fig. 3 illustrates a phonograph record cutter made by mounting a stylus 22 in the 95 end of member 18. In this arrangement the electric impulses are imposed upon coil 11, the magnetic field in the center of coil 11 causes rods 14 and 15 to vary their respective lengths and to move the stylus 22, 100

whereby a groove is cut in the blank 23 which is rotated by plate 24.

What I claim as new and desire to secure by Letters Patent of the United States, is:

- 5 1. The combination of means for producing a magnetic field, and two members rigidly mounted at one end and respectively operable to contract and elongate when subjected to said field.
- 10 2. The combination of means for producing a magnetic field, a plurality of magnetostrictive members rigidly mounted at one end and respectively operable to contract and elongate when subjected to said field, a sound diaphragm, and driving means arranged between said diaphragm and said magneto-strictive members.
- 15 3. The combination of means for producing a magnetic field, a plurality of magneto-strictive members rigidly mounted at one end and respectively operable to contract and elongate when subjected to said field, a sound diaphragm and driving means arranged between said diaphragm and the free ends of said magneto-strictive members.
- 20 4. The combination of means for producing a magnetic field, two magneto-strictive members rigidly mounted at one end and operable to oppositely vary their respective lengths when subjected to said field, a sound diaphragm, and resilient driving means arranged between said diaphragm and the free ends of said magneto-strictive members.
- 25 5. The combination of means for producing a magnetic field, two magneto-strictive members each rigidly mounted at one end and respectively operable to contract and elongate when subjected to said field, and a movable member in operative relation with the other end of each of said magneto-strictive members.
- 30 6. The combination of means for producing a magnetic field, two magneto-strictive members rigidly mounted at one end and respectively operable to contract and elongate when subjected to said field, a movable member, and driving means arranged between said movable member and the free ends of said magneto-strictive members.
- 35 50 50. In witness whereof, I have hereunto set my hand this 21st day of January, 1929.

JAMES T. SERDUKE.
